UNITED STATES PATENT OFFICE.

SAMUEL MILTON SUMAN, OF RIVERSIDE, CALIFORNIA.

WATER-FILTER.

SPECIFICATION forming part of Letters Patent No. 623,439, dated April 18, 1899.

Application filed November 16, 1898. Serial No. 696,627. (No model.)

To all whom it may concern:

Be it known that I, SAMUEL MILTON SUMAN, of Riverside, in the county of Riverside and State of California, have invented a new and 5 Improved Water-Filter, of which the following is a full, clear, and exact description.

The object of the invention is to provide a new and improved water-filter which is simple and durable in construction, very effective in operation, and arranged to filter the water several times to obtain perfectly pure water, the filter being adapted for use in dwellings, hotels, public water-supply systems, soldiers' barracks, miners' camps, &c.

15 The invention consists of novel features and parts and combinations of the same, as will be fully described hereinafter and then pointed out in the claims.

Reference is to be had to the accompanying 20 drawings, forming a part of this specification, in which similar characters of reference indicate corresponding parts in all the views.

Figure 1 is a longitudinal sectional elevation of the improvement. Fig. 2 is a transverse section of the same on the line 2 2 in Fig. 1. Fig. 3 is a plan view of one of the charcoal-baskets, and Fig. 4 is a sectional side elevation of the same.

The improved water-filter illustrated in the 30 drawings is preferably in the shape of a box A of suitable material and size and preferably placed in an inclined position, as indicated in Fig. 1. In the upper end of the box is arranged an inlet-passage B, formed in the 35 top with a strainer C, into which passes the water from a suitable supply, the strainer retaining such solid matter as pieces of wood, animals, or the like, the water flowing down the passage B to the bottom of the box and 40 to an inlet D for a filter-bed E, provided in its bottom with a heavy screen-bottom E', on which rests gravel E², sand E³ being in the upper portion, a screen E⁴ separating the sand from the gravel.

45 The filter-bed E is provided on top with an overflow E⁵, causing the water rising through the filter-bed to pass in a thin stream over the said overflow into a passage F, extending downward on the lower side of the filter-bed, 50 to lead at its lower end into a second inlet D' for a second filter-bed E⁶, similar in construction to the filter-bed E previously men-

tioned. The filter-bed E discharges the water over its overflow into an upright passage F', which connects at its lower end with an 55 inlet D² of another filter-bed E⁷, similar to the filter-beds E and E⁶. The filter-bed E⁷ discharges the water over an overflow into another passage F², connected at its lower end with an inlet D³ for a filter-bed E⁸, similar 60 to the filter-beds E⁶ and E⁷. The water overflowing from said filter-bed E⁸ passes into the upper end of a charcoal-basket G, filled with charcoal H and provided with a perforated bottom G', through which passes the water 65 to an inlet D⁴ for another filter-bed E⁹, similar to the filter-beds previously described. The water overflowing from the filter-bed E⁹ passes to a second charcoal-basket G², likewise filled with charcoal and provided with a 70 bottom screen G', through which the water passes to an inlet D⁵ for a filter-bed I², having a screen-bottom I', on which rests pure white sand. After the water passes through the sand it accumulates above the same and 75 finally flows through an outlet J and passes in a purified condition to a suitable place of discharge. The overflows E⁵ of the filter-beds E⁸ and E⁹ deliver the water from the said filter-beds in a thin stream upon the corrugated 80 top portions G³ for the charcoal-baskets G, so that the water is spread as much as possible before passing into the baskets and through the charcoal contained therein.

When the device is used, the water passing 85 from a suitable supply through the strainer C and passage B into the inlet D rises through the gravel E² and the sand E³, so as to free the water of a greater portion of its impurities. The water in the top of the filter-bed 90 finally flows over the overflow E⁵ in a thin stream, so as to be exposed to air and light, which act as a germicide for destroying bacteria, &c. The water now flows down the passage F to the inlet D', to again rise through 95 the gravel and sand and to be again exposed to the action of air and light while flowing in a thin stream over the overflow E⁵ of the second filter-bed E⁶. This operation is repeated through the next filter-beds E⁷ and E⁸, and the water from the latter finally passes in a thin stream over the overflow E⁵ and the corrugated top portion G³ into the charcoal-basket G and through the charcoal contained

therein. The water then flows through the gravel and sand in the next filter-bed E⁹, then through the second charcoal-basket G², and, finally, through the pure white sand in 5 the last filter-bed I, to be discharged through the pipe J.

It is evident from the foregoing that any desired number of filter-beds E may be arranged one alongside the other, with passages 10 F between, to cause the water to flow from the top of one filter-bed to the bottom of the next one and rise through the filter-bed instead of flowing down through the filter-bed. By the water passing through the several filter-beds and the charcoal-baskets a perfect 15 purification of the water takes place.

In the lower ends of the inlets D D' D² D³ 20 D⁴ D⁵ are arranged faucets K for discharging the impurities settling in said inlets.

25 It will further be seen that the several filter-beds are open at the top, with the exception of the last filter-bed I, which is preferably closed or covered to keep out dust, &c.

When it is desired to clean the apparatus, 25 the faucets K are opened and water is sprayed into the filter-beds from the top to cause the collected impurities in the sand and gravel to flow through the screen-bottom E' into the corresponding inlet for this filter-bed and 30 finally pass to the faucet K and out of the same. Thus the gravel and sand remain undisturbed in the filter-beds and still a perfect washing thereof takes place. It will also be understood that the filter can be readily 35 constructed in different sizes for family use, hotels, water-supply systems, &c., according to the amount of water required for use.

Having thus fully described my invention, I claim as new and desire to secure by Letters 40 Patent—

45 1. A water-filter, comprising a series of filter-beds each having an inlet at the bottom and an overflow at the top, and charcoal-receptacles between adjacent filter-beds and arranged to receive the water from one filter-bed and to deliver the water to the inlet of the next following filter-bed, each charcoal-receptacle being provided with a top portion over which the water flows, substantially as 50 described.

55 2. A water-filter, comprising a series of filter-beds, having inlets at the bottom and overflows at the top, the filter being provided with passages between adjacent filter-beds to connect the overflow of one filter-bed with the inlet of the next following one, faucets arranged in the lower ends of the inlets for discharging the impurities settling therein, the last filter-bed being closed at the top and provided with a discharge-pipe, substantially as 60 described.

65 3. A water-filter, comprising a series of filter-beds, each having an inlet at the bottom and an overflow at the top, and charcoal-basket between adjacent filter-beds, and arranged to receive the water from the overflow of one filter-bed and to deliver the water to the inlet of the next following filter-bed, each basket being provided with a corrugated top portion over which flows the water from the 70 overflow of the preceding filter-bed, to pass into the basket and through the charcoal contained therein, substantially as shown and described.

75 4. In a water-filter, a charcoal-basket having a screen-bottom and a corrugated top portion over which the water flows to pass into the basket, substantially as shown and described.

80 5. A water-filter, comprising a box arranged in an inclined position, the said box being provided at its upper end with an inlet-passage having a strainer, a series of filter-beds arranged in the box and each having an inlet at the bottom and an overflow at the top, a 85 charcoal-receptacle located between adjacent filter-beds and arranged to receive the water from the overflow of one filter-bed and to deliver the water to the inlet of the next following filter-bed, each charcoal-receptacle being provided with a top portion over which flows the water from the overflow of the preceding filter-bed to pass into the charcoal-receptacle, the filtering-bed at the lower end of the box being closed at the top and provided with a discharge-pipe, substantially as 90 95 shown and described.
